[57] CLAIM

The ornamental design for a combined word processor-printer, as shown and described.

DESCRIPTION

FIG. 1 is a perspective view of the combined work processor-printer with the cover open showing our new design;

FIG. 2 is a perspective view thereof with the cover closed;

FIG. 3 is a front elevational view thereof with the cover closed;

FIG. 4 is a rear elevational view thereof with the cover closed;

FIG. 5 is a top plan view thereof with the cover closed;

FIG. 6 is a bottom plan view thereof with the cover closed;

FIG. 7 is a right side elevational view thereof with the cover closed;

FIG. 8 is a left side elevational view thereof with the cover closed;

FIG. 9 is a perspective view thereof with the cover omitted for purposes of disclosure;

FIG. 10 is a top plan view thereof with the cover omitted for purposes of disclosure;

FIG. 11 is a bottom plan view thereof with the cover omitted for purposes of disclosure;

FIG. 12 is a rear elevational view thereof with the cover omitted for purposes of disclosure;

FIG. 13 is a rear elevational view thereof with the cover removed;

FIG. 14 is a right side elevational view thereof with the cover omitted for purposes of disclosure;

FIG. 15 is a left side elevational view thereof with the cover omitted for purposes of disclosure.
